UNITED STATES PATENT OFFICE.

BARTON W. SCOTT, OF SAN JOSE, CALIFORNIA.

ACETYLENE-GAS GENERATOR.

No. 842,345.

Specification of Letters Patent.

Patented Jan. 29, 1907.

Application filed November 3, 1905. Serial No. 285,713.

To all whom it may concern:

Be it known that I, BARTON W. SCOTT, a citizen of the United States, and a resident of San Jose, in the county of Santa Clara and State of California, have invented a new and Improved Acetylene-Gas Generator, of which the following is a full, clear, and exact description.

The purpose of the invention is to provide an apparatus for generating gas from carbid which will be simple, compact, and thoroughly safe and so constructed that the feed of carbid may be made automatic when desired, but wherein the feed of carbid at all times will be under the control of the attendant.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a vertical section through the complete machine. Fig. 2 is an enlarged horizontal section taken practically on the line 2 2 of Fig. 1. Fig. 3 is a side elevation of the bottom portion of the machine. Fig. 4 is a partial vertical section through the upper portion of the machine, showing the automatic feed-valve closed and the controlling-valve open. Fig. 5 is a detail view of a guide device employed to prevent the one section of the gasometer turning in the other, and Fig. 6 is a detail vertical section taken practically on the line 6 6 of Fig. 2 and illustrating the guides for the controlling-valve.

A represents the body, and B the bell-section, of the gasometer, and in order that the bell-section may readily move in the body-section of the gasometer friction-rollers 10 are preferably placed at the lower portion of the bell B, which rollers 10 are adapted for engagement with the body of the gasometer, while at the upper portion of the gasometer friction-rollers 11 are suitably secured, having bearing against the bell-section B, as shown in Fig. 1.

The bell-section B of the gasometer has a dome-top 12, provided with a central opening 13, and the said opening is surrounded by a collar 14, closed at its upper portion by a cover 15, which cover is usually controlled by a screw 16, mounted to turn in a yoke 17,

carried by the said collar, as is also shown in Fig. 1. The bell-section B of the gasometer is prevented from turning in the body-section usually by securing a bracket 18 to the outer surface of the bell B near its upper end, to which bracket a downwardly-extending rod 19 is attached, the said rod being adapted for vertical movement in the bifurcated section of a bracket 20, which is secured to the outer face of the body-section A of the gasometer, as is shown in Figs. 1 and 5.

A cone-shaped partition 21 is secured to the inner wall of the bell-section B of the gasometer near its upper end, forming thereby a chamber C for the reception of carbid, and this partition 21 is provided with a central opening 22, which is at the apex of the cone. Below the opening 22 for the chamber C a funnel 23 is located, supported from the bottom portion of the partition 21 by suitable hangers 24.

Lugs 25 extend down from the partition 21, as is shown in Figs. 1 and 2, and between these lugs a feed-valve D is pivoted, which valve is provided with a shovel-shaped inner end 26, located below the outlet-opening 22 of the carbid-chamber C, and the said valve D is provided at its outer end with a weight 27. The said weight is sufficiently heavy to close the shovel-shaped inner section 26 against the outlet portion of the chamber C when the said weight is free to act, as is shown in Fig. 4.

The supply of carbid from the chamber C to the interior of the gasometer below the partition 21 is regulated by a controlling-valve E. This controlling-valve E consists of an inner blade-section 28, an outer knob 30, and an intermediate rod-section 29, the said rod-section being mounted to slide in a stuffing-box 31, forming a portion of the bell-section B of the gasometer. The blade-section 28 of the controlling-valve E is mounted to slide in ways 32, formed at the lower ends of hangers 33, which hangers are secured to the partition 21, as is shown in Fig. 1, the said guide device for the controlling-valve E being particularly shown in Fig. 6.

The blade 28 of the controlling-valve E can be pushed inward so as to completely close the outlet-opening 22 of the carbid-chamber C, or it may be drawn far enough out to entirely or partially uncover the said outlet-opening, and when the outlet-opening 22 of the carbid-chamber C is wholly or partly open the carbid passes from the chamber C

to the shovel end 26 of the feed-valve D and is directed thereby to a side portion of the funnel 23, as is illustrated in Fig. 1.

The depth of the carbid in the chamber C may be ascertained at any time by means of a measuring device carried by the bell-section B of the gasometer. This measuring device consists of a rod 34 of predetermined length, having a knob 35 at its outer end, and the said rod is made to slide in a stuffing-box 36, located in the dome-top 12 of the said bell B, as is shown in Fig. 1, and within the carbid-chamber C the rod 34 is provided with a foot 37. Supposing the foot 37 to be buried down in the carbid and it is desirable to know how much carbid still remains in the chamber C, the rod 34 is drawn outward until the foot 37, for example, is in engagement with the bottom of the stuffing-box 36, and then the rod 34 is pressed downward until the foot 37 engages with the carbid, whereupon the distance between the knob 35 and the stuffing-box 36 will represent the depth of the carbid in the said chamber C.

25 A blow-off pipe 38 is employed, which permits the gas to escape should the gasometer become too heavily charged. This blow-off pipe for the major portion of its length is located within the bell B of the gasometer, being suitably supported at its bottom portion by a bracket 39. The upper portion of the pipe 38 extends out through the upper portion of the said bell B of the gasometer and may be carried wherever desired. When the 35 charge of gas in the gasometer is sufficient to elevate the bell-section B to such an extent that the lower end of the pipe 38 is carried out of the water which is contained in the body of the gasometer, the gas will pass out 40 through the pipe 38, and when the overpressure is relieved the bell will again drop and the lower end of the relief-pipe 38 will be again immersed in the water contained in the gasometer.

45 A service-pipe 40, which is adapted to carry off the gas from the gasometer, extends vertically therein and is usually supported by braces 41, connected with the pipe by a pinch-collar 42, for example, and the upper end of 50 the pipe 40 extends a sufficient distance above the level of the water in the gasometer to receive gas at all times while the machine is working. The lower end of the service-pipe extends out through the body of the 55 gasometer, as is shown in Fig. 1, and the upper end of the pipe 40 is below the weight 27, carried by the feed-valve D.

When the outlet-opening 22 of the carbid-chamber C has been regulated by the controlling-valve E and the bell of the gasometer has dropped sufficiently into the body-section to cause the weight of the feed-valve D to engage with the upper end of the pipe 40, the shovel-shaped inner end 26 of the said 65 valve D will be carried downward, occupying

the inclined position shown in Fig. 1, and the outlet-opening of the carbid-chamber will be uncovered by the said shovel-shaped section 26 of the valve, and the carbid will flow into the hopper or funnel 23 and from thence 70 into the water in the body of the gasometer. When enough gas has been generated to raise the bell of the gasometer a certain distance, the weight 27 of the feed-valve D will be carried from engagement with the service-pipe 75 40, and the said weight will then cause the shovel-shaped inner end 26 of the feed-valve to be carried upward to close the outlet-opening of the carbid-chamber C, as is shown in Fig. 4. Thus it will be observed that the 80 said feed-valve is practically automatic in its action and that the amount of carbid to be fed from the chamber C is under the control of the attendant through the medium of the controlling-valve E. When the bell B of the 85 gasometer is at its lowest point in the body-section A, the said bell rests upon brackets 43, located at the inner lower portion of the said body, as is shown in Fig. 1.

A valve 44 is located at the lower portion 90 of the body of the gasometer, and adjacent to it a pipe 45 is introduced into the body of said gasometer, which pipe is provided with a valve 46. The valve 44 is a discharge-valve, as through it the water is drawn off from the 95 gasometer when it becomes too thick or chalky, and the pipe 45 is a supply-pipe, and through it the water enters the gasometer. The pipe 45 may be connected with any source of water-supply, and the valve 44 may be connected with a sewer, or the equivalent thereof, if desired.

Having thus described my invention, I claim as new and desire to secure by Letters Patent—

1. In an acetylene-gas machine, a gasometer, the bell-section of which is provided with a dome-top and with an inverted-cone-shaped partition near its upper end forming with the top a carbid-chamber, said partition having a central opening at its apex, a funnel below the opening of the said partition, a weighted and shovel-shaped valve pivoted to lugs projecting from the partition, said valve being adapted to close the opening of the partition when in one position and to discharge into the funnel when in another position, and a service-pipe extending up into the bell and adapted to engage the said valve.

2. In an acetylene-gas machine, a gasometer, the bell-section of which is provided at upper end with a receiving-chamber having an inlet and outlet, a funnel beneath the outlet of the said chamber, a sliding valve for controlling the outlet of the chamber, said valve being mounted in the bell-section of the gasometer, a shovel-shaped feed-valve pivoted to the bottom of the chamber and provided with a weight at one end, and a service-pipe extending up into the bell-section

and adapted to engage the weight of the valve, the valves being located between the chamber and funnel.

3. In an acetylene-gas machine, a gasometer, the bell of which is formed in its upper end with a carbid-chamber having a hopper-shaped bottom, said bottom having an opening therein, a pivoted and counterbalanced valve constructed to fit upon the hopper-shaped bottom of the carbid-chamber around the opening thereof to close the same, means carried by the body of the gasometer for opening the valve when the bell descends, and a valve mounted to slide between the pivoted valve and the lower end of the hopper-shaped bottom of the carbid-chamber to wholly or partially close the opening therein.

4. In an acetylene-gas machine, a gasometer, the bell of which is provided with a carbid-chamber in its upper end, said chamber having an apertured hopper-shaped bottom, a pivoted and counterbalanced shovel-shaped valve below the bottom of the carbid-chamber, means carried by the body of the gasometer for opening the valve when the bell descends, and a valve mounted to slide in guideways at one side of the discharge-opening of the carbid-chamber, and adapted to wholly or partially close the said opening.

5. An acetylene-gas machine, comprising a gasometer, the bell of which is formed with a carbid-chamber in its upper end, the chamber having a hopper-shaped bottom having a

discharge-opening therein, means for guiding the bell in the body, a pivoted and counterbalanced valve below the discharge-opening of the carbid-chamber, means carried by the gasometer-body for opening the valve when the bell descends, a sliding valve for wholly or partially closing the said discharge-opening, and a blow-off pipe having its major portion arranged within the gasometer-bell with its upper end projecting out through said bell.

6. An acetylene-gas machine, comprising a gasometer, the bell of which is formed with a carbid-chamber in its upper end, the chamber having an apertured hopper-shaped bottom, means for guiding the bell in the body, means for preventing said bell from turning in said body, a pivoted and counterbalanced valve below the opening of the carbid-chamber, means carried by the gasometer-body for opening the valve when the bell descends, a sliding valve for wholly or partially closing the opening of the carbid-chamber, and a blow-off pipe arranged within the bell of the gasometer and extending out through the same at the upper end thereof.

In testimony whereof I have signed my name to this specification in the presence of two subscribing witnesses.
